(57) **CLAIM**

The ornamental design for a checkout station, as shown.

DESCRIPTION

FIG. 1 is a perspective view of a checkout station showing my design;

FIG. 2 is a left side view of the checkout station shown in FIG. 1;

FIG. 3 is a right side view of the checkout station shown in FIG. 1;

FIG. 4 is a front view of the checkout station shown in FIG. 1;

FIG. 5 is a back view of the checkout station shown in FIG. 1; and,

FIG. 6 is a top view of the checkout station shown in FIG. 1.

The broken lines represent portions of the checkout station that form no part of the claimed design.

1 Claim, 6 Drawing Sheets
